UNITED STATES PATENT OFFICE.

JOHN J. MACKLE, OF TORONTO, CANADA.

FOLDING COT.

SPECIFICATION forming part of Letters Patent No. 786,908, dated April 11, 1905.

Application filed May 3, 1904. Serial No. 206,217.

To all whom it may concern:

Be it known that I, JOHN J. MACKLE, of the city of Toronto, county of York, Province of Ontario, Canada, have invented certain new and useful Improvements in Folding Cots, of which the following is a specification.

The object of my invention is to devise a simple, strong, and convenient folding cot; and it consists, essentially, of the details of construction of the connections between the bottom frame and the ends and of the connections between the sides, the ends, and the bottom frame, substantially as hereinafter more specifically described and then definitely claimed.

Figure 1 is a perspective view of my improved folding cot. Fig. 2 is a cross-section showing one of the sides swung down. Fig. 3 is a side elevation of the cot folded, and Fig. 4 an end elevation of the cot folded. Fig. 5 is a perspective detail showing the connection between one of the bearing-pieces and the cot end. Fig. 6 is a similar view showing the connection between the sides and ends of the cot.

In the drawings like letters of reference indicate corresponding parts in the different figures.

The cot comprises a bottom frame A, the ends D, and the sides E. The bottom frame may carry a woven-wire spring or be provided with other suitable means for supporting the mattress B. (See Figs. 3 and 4.) The bottom frame may be made of any suitable material and of any construction, but is shown as formed of steel or iron bars of any suitable shape. Braces C are secured across the corners, as shown in Fig. 1, and each brace has journaled thereon a caster a, upon which the cot may run when folded, as hereinafter described.

The cot ends D may be of any ordinary construction, but are shown with their posts F flattened adjacent to the bottom frame, as indicated at b. Against the flattened parts of the posts the bearing-pieces G impinge. Of course if the posts were round the bearing-pieces would be correspondingly shaped. These bearing-pieces extend, as shown, some distance above the bottom frame and are secured thereto in any suitable manner, preferably by having horizontal straps e formed integral therewith and riveted or bolted to the sides of the

bottom frame. The lower part of each bearing-piece has a V-shaped claw d formed thereon. These claws are adapted to engage the headed studs e, secured to the posts F. Each bearing-piece has a slot f formed therein close to its outer edge. These slots receive the pins g, secured to the ends of the lower rails H of the cot sides E, toward their outer edges. The upper rails I of the cot sides have downwardly-depending hooks or lugs h formed on or secured thereto, which are adapted to engage the keepers i, secured to the upper ends of the posts F. From this construction it will be seen that the claws d and studs e form a detachable connection between the lower parts of the bearing-pieces G and the cot ends and that the posts and the cot ends are held in close engagement with the bearing-pieces by the rails I. This construction makes the cot when set up exceedingly stiff and strong. If it be desired to use the cot with one side down, the side is lifted to withdraw the hooks h from the keepers i, the pins g, moving vertically in the slots f, permitting this movement. The side may now be swung down to the position shown in Fig. 2. As the slots f are located toward the outer sides of the bearing-pieces, the cot side hangs down vertically, the offsetting of the slot enabling it to pass clear of the side of the bottom frame. For convenience in folding and for the further purpose of strengthening and stiffening the cot I provide the links K, pivotally connected with the sides of the bottom frame and with the posts of the cot ends below the same. If it be desired to fold the cot completely, the sides are lifted to disengage their hooks from the keepers and then folded inwardly on top of the mattress, the slots f permitting the sides to accommodate themselves exactly to the thickness of the mattress and bedclothing. The bottom frame at one end is then lifted to disengage the claws d from the studs e, whereupon the cot end may be swung on the links K to a position on top of the sides E. The other end may be similarly disengaged and then folded in, as shown in Figs. 3 and 4. The folded cot now rests on the casters d, and being, as will be seen, of comparatively little thickness may be easily pushed away under a bed or sofa.

The most important feature of my invention is the construction of the bearing-pieces extending well above the bottom frame and having the claws at their lower ends engaging the headed studs on the cot ends, the cot ends being held in engagement with the bearing-pieces by the rails I, which are detachably engaged with the upper parts of the posts.

Another important feature is the arrangement by which the cot sides may be swung outwardly and downwardly or turned inwardly and laid upon the mattress, together with the arrangement of the slots by which the sides accommodate themselves to the thickness of the mattress and bedclothing.

I do not desire to confine myself to the exact details of construction shown, as these may be varied somewhat without departing from the spirit of my invention. For instance, as shown in Fig. 5, the slot is not necessarily cut right through the bearing-piece, and a cut *m* is formed into one side of the slot, through which the pin *g* may be inserted or removed. If both sides be thus removed, the cot may be employed as a bed. In this case it is desirable to provide hooks *l* on the posts *F*, which may be engaged with the headed pins *n* on the bearing-pieces. The cot will then be perfectly rigid without the sides. (See Fig. 5.)

30 What I claim as my invention is—

1. In a folding cot the combination of a bottom frame; a vertical bearing-piece secured to each corner of the frame and facing toward the end; cot ends having bearing-surfaces which the bearing-pieces are adapted to engage; detachable connections between the lower ends of the bearing-pieces and the cot ends; and side bars detachably connected to the cot ends, substantially as described.

40 2. In a folding cot the combination of a bottom frame; a vertical bearing-piece secured to each corner of the frame and facing toward the end; cot ends having bearing-surfaces which the bearing-pieces are adapted to engage; a claw formed at the lower end of each bearing-piece; headed studs on the ends with

45 which the said claws may be engaged; and side bars detachably connected to the cot ends, substantially as described.

50 3. In a folding cot the combination of a bottom frame; a vertical bearing-piece secured to each corner of the frame and facing toward the end; a vertical slot being formed in each bearing-piece; cot ends having bearing-sur-

55 faces which the bearing-pieces are adapted to engage; detachable connections between the lower ends of the bearing-pieces and the cot ends; cot sides having detachable connection with the ends at or near the top; and pins on

the cot sides engaging the slots in the bearing-pieces, substantially as described.

4. In a folding cot the combination of a bottom frame; a vertical bearing-piece secured to each corner of the frame and facing toward the end, a vertical slot being formed in each bearing-piece near its outer side; cot ends having bearing-surfaces which the bearing-pieces are adapted to engage; detachable connections between the lower ends of the bearing-pieces and the cot ends; cot sides having detachable connection with the ends at or near the top; and pins on the cot sides engaging the slots in the bearing-pieces, substantially as described.

5. In a folding cot the combination of a bottom frame; a vertical bearing-piece secured to each corner of the frame and facing toward the end; a vertical slot being formed in each bearing-piece; cot ends having bearing-surfaces which the bearing-pieces are adapted to engage; a claw formed at the lower end of each bearing-piece; headed studs on the ends with which the said claws may be engaged; cot sides having detachable connections with the ends at or near the top; and pins on the cot sides engaging the slots in the bearing-pieces, substantially as described.

6. In a folding cot the combination of a bottom frame; a vertical bearing-piece secured to each corner of the frame and facing toward the end; a vertical slot being formed in each bearing-piece; cot ends having bearing-surfaces which the bearing-pieces are adapted to engage; a claw formed at the lower end of each bearing-piece; headed studs on the ends with which the said claws may be engaged; cot sides having detachable connections with the ends at or near the top; pins on the cot sides engaging the slots in the bearing-pieces; and a link at each corner pivoted on the side of the bottom frame and the side of the cot end below its connection with the bottom frame, substantially as described.

7. In a folding cot the combination of a bottom frame; a vertical bearing-piece secured to each corner of the frame and facing toward the end; cot ends having bearing-surfaces which the bearing-pieces are adapted to engage; detachable connections between the lower ends of the bearing-pieces and the cot ends; and hooks and pins whereby the upper parts of the bearing-pieces may be locked to the cot ends, substantially as described.

Toronto, April 27, 1904.

JOHN J. MACKLE.
